(57) **CLAIM**

The ornamental design for a personal mobility vehicle, as shown and described.

DESCRIPTION

FIG. 1 is a top, front, and left perspective view of a personal mobility vehicle of our design;
FIG. 2 is a front elevation view thereof;
FIG. 3 is a rear elevation view thereof;
FIG. 4 is a right side elevation view thereof;
FIG. 5 is left side elevation view thereof;
FIG. 6 is a top plan view thereof; and,
FIG. 7 is a bottom plan view thereof.
All features illustrated in broken lines form no part of the claimed design.
